CALENDAR

Martin E. Trolle, St. Paul, Minn., assignor to
 Brown & Bigelow, St. Paul, Minn., a corpora-
 tion of Minnesota

Application January 2, 1941, Serial No. 372,703

2 Claims. (Cl. 40—121)

My invention relates to an improvement in display calendars wherein it is desired to provide a calendar of the display easel type trimmed with transparent or translucent plastic through which light may be transmitted.

Many different types of easel calendar displays have been produced in recent years, this type of calendar being extremely popular at the present time. Certain of these calendars have many of the same characteristics which I desire to provide in my present construction of calendar and the general form of the same is similar to those which have been previously manufactured.

It is the object of my invention to provide a calendar of the easel type embodying a background plate of suitable design to support a calendar display pad or the like. This display is equipped with a plastic portion extending through the body of the same or extending about the body. This plastic portion is transparent or translucent and permits light from behind the easel to shine through the plastic, providing an extremely attractive display. Not only does this construction enhance the appearance of the calendar, but also it permits the transmission of light from behind the calendar to the front of the calendar to better illuminate the same.

It is a feature of my invention that the transparent or translucent plastic used as trimming for my calendar projects forwardly from the front surface of the calendar so that light transmitted therethrough may to some extent illuminate the face of the calendar. The light thus transmitted may be small but may be just sufficient to make the face of the calendar clearly visible instead of indistinct.

It is a feature of my invention that the plastic may be secured to the calendar by riveting the plastic through suitable recesses in the calendar or by frictionally supporting the plastic strips in grooves or recesses in the body of the calendar. Thus the plastic may be easily and quickly attached to the calendar at an extremely low cost as is necessary in a construction of this type because of the fact that the calendars must be sold to the customer reasonably in order that they may be given away in quantities.

It is a further feature of one form of my invention that the plastic may serve as a means of holding the calendar pad sheets in parallel relation to the calendar background. In this construction the plastic rim overlies the lower edge of the calendar sheets and holds the sheets in proper position upon the background. As the

sheets of the pad are usually secured to the background sheet along one edge thereof only, the plastic strip may serve as a means of holding the opposite edge adjacent the background sheet to hold the pad in a flat condition.

It is a further feature of my invention to provide a calendar trimmed with transparent or translucent material which may be colored to color the light passing therethrough. As this plastic trim extends forwardly from the front surface of the calendar, and as the plastic is so supported as to permit light to pass from the rear of the calendar therethrough, a glow or hue of color is transmitted to the calendar pad, thus improving the appearance thereof. The calendar background sheet may be of one color, the calendar pad itself may be white, or of another color, and the light shining through the transparent plastic will lend to these two contrasting elements a red hue or color which will greatly improve the appearance of the display.

These and other objects and novel features of my invention will be more clearly and fully set forth in the following specification and claims.

25 In the drawings forming a part of this specification:

Figure 1 is a front elevational view of one form of calendar showing the plastic trim attached thereto.

30 Figure 2 is a cross-sectional view centrally through the calendar of Figure 1, the position of the section being indicated by the line 2—2 of Figure 1.

Figure 3 is a rear view of the calendar shown in Figures 1 and 2, a portion of the calendar being broken away and the easel support being bent up into its inoperative position.

40 Figure 4 is a sectional view through the plastic trim and through a portion of the calendar, the view being enlarged to better illustrate the construction thereof and the position of the section being indicated by the line 4—4 of Figure 3.

Figure 5 is an enlarged cross sectional view through a portion of the plastic trim and the calendar, the position of the section being indicated by the line 5—5 of Figure 3.

Figure 6 is a front elevational view of a modified form of construction.

50 Figure 7 is a cross-sectional view centrally through the calendar of Figure 6, the position of the section being indicated by the line 7—7 of Figure 6.

Figure 8 is a front view of another modified form of construction.

55 Figure 9 is a central cross-sectional view of the

calendar of Figure 8, the position of the section being indicated by the line 9—9 of Figure 8.

Figure 10 is a rear view of a portion of the calendar shown in Figures 8 and 9, with the easel support bent into inoperative position.

Figure 11 is a front view of another modified form of calendar.

Figure 12 is a cross-sectional view through the calendar of Figure 11, the position of the section being indicated by the line 12—12 of Figure 11.

Figure 13 is a rear view of a portion of the calendar shown in Figures 11 and 12, the support for the easel being bent into inoperative position.

Figure 14 is a sectional view on the line 14—14 of Figure 10, showing the manner in which the plastic trim is secured in place.

Figure 15 is a view similar to Figure 14, showing another form of plastic trim used in conjunction with the calendar.

Figure 16 is a view similar to Figures 14 and 15, showing another form of plastic trim which may be employed.

Figure 17 is a view similar to Figures 14, 15 and 16, showing still another form of plastic trim which may be used in conjunction with the calendar.

The calendar A is provided with a background sheet or member 10 having rearwardly extending flanged edges 11 extending across the upper edge of the same and a flanged edge 12 extending along the top portion of the sides of the background sheet 10. An offset portion 13 is provided near the bottom of the background sheet 10 extending throughout most of the width of the same. This offset portion provides a recess for containing a calendar pad 14 which may be secured thereto by any suitable means such as by the ears 15. The ears 15 extend through the calendar pad 14 and are bent to hold the sheets forming the calendar pad in proper position overlying the offset portion 13 of the background sheet 10.

A substantially T-shaped supporting element 16 is cut from the body of the background sheet within the offset portion 13 and is connected to the background sheet at the base or T as indicated by the numeral 17. This support 16 is bent rearwardly as best illustrated in Figure 2 of the drawings, to provide a support for holding the background sheet 10 in an upwardly and rearwardly inclined position as illustrated. As the stand 16 is cut from the body of the offset portion which is covered by the calendar pad, the cut-away portion in the background sheet 10 is concealed by the calendar pad when the calendar is viewed from the front thereof.

Along the lower edge of the background sheet 10, I provide a rearwardly bent flange 19 which extends the length of the offset portion 13 of the background sheet. Thus the lower edge of the background sheet adjacent the offset portion 13 is bent rearwardly so as to permit the lower edges of the calendar pad sheets to extend flat with respect to the remainder of the calendar pad sheets and to perhaps be bent slightly rearwardly by the plastic trim in the manner which will be later fully explained.

Extending along the side edges of the backing sheet 10 between the lower edge of the backing sheet 10 and the lower end of the edge flange 12, I provide offset flanges 20. These flanges 20 as best illustrated in Figure 4 of the drawings, are spaced rearwardly from the body of the back-

ground sheet 10 and extend substantially parallel to this background sheet 10. A pair of spaced notches 21 are provided at the flanges 20, these notches or recesses being of larger dimensions at a point inwardly spaced from the outer edge of the flanges 20 than at the extreme edge 20. This construction is designed to prevent the plastic trim from being pulled transversely from the background sheet 10, the plastic trim being pulled longitudinally from the notches in the edge thereof. Openings through the flanges 20 may be provided in place of the notches 21 if it is so desired.

The plastic trim is provided with a decorated forward surface, the body 22 of the trim being formed with two side elements 23 designed to extend along the opposed side edges of the display calendar and a bottom connecting strip 24 connecting the opposed side members 23. The sides 23 of the plastic trim 22 are grooved at 18 to form an attractive design as will be noted from an examination of Figures 1 and 4 of the drawings, and are slotted at 28.

In order to hold the plastic trim 22 to the background sheet 10, I provide lugs or studs 25 extending rearwardly from the sides 23 of the plastic trim 22 to extend through the notches or recesses 21. The plastic trim is provided with these studs or lugs which are of a shape to fit through the recesses such as 21, and after their insertion the studs or lugs 25 may be flattened down with a heated die or the like, in order to spread this lug or stud and to rivet the plastic trim to the calendar body. When the studs or lugs have been riveted over, as illustrated in Figure 4 of the drawings, it will be seen that the trim 22 is definitely fixed to the background sheet 10.

The bottom strip 24 of the plastic trim is formed as best illustrated in Figure 2 of the drawings. It will be noted that the body of this strip 24 extends below the lower edge of the background sheet 10 and is provided with an upwardly extending lip 26 on its forward surface designed to overlie the lower edges of the calendar pad sheets 14. The lip 26 engages the lower edge of the calendar pad sheets 14 while the attaching lugs 15 extend through the sheets near the upper edge thereof and thus the sheets 14 are held along both edges so as to remain constantly flat. As there is a tendency for the sheets 14 to curl if they are not held in flat relation, this lip 24 is very important in the present combination. It will be noted that the flanged edge 19 adjacent the lower ends of the calendar sheets 14 is bent inwardly as has been previously described so as to provide a substantial space for the lower edges of the calendar sheet between the backing sheet 10 and the lip 26. This construction prevents the wedging of the lower edges of the sheets into a narrow space from which the sheets could not easily be withdrawn.

It will be noted that the plastic trim extends forwardly from the backing sheet 10 particularly along the lowermost edge thereof. Light from the rear of the calendar is permitted to pass through the translucent or transparent plastic and is diffused thereby, some of the light being directed toward the calendar pad sheets 14. Thus not only does the light shining through the plastic provide an attractive appearance as though this edge were illuminated by artificial illuminating means, but also a glow of light is transmitted over the surface of the calendar pad. If the plastic is of colored material, it imparts a colored

glow to the calendar pad to illuminate the indicia thereupon.

In Figures 6 and 7 of the drawings, I disclose a modified form of calendar construction designated in general by the letter B. This calendar is similar to the calendar previously described and designated by the letter A with the exception that the plastic trim extends entirely around the backing sheet rather than partially around the same. In the calendar B, the backing sheet 27 is of any desired outline configuration and is provided with an offset or recessed portion 29 to accommodate the calendar pad 30. The calendar pad 30 is secured to the recessed portion 29 of the backing sheet 27 by any suitable means, such as the attaching ears 31 which extend through the sheets and are bent over to clamp the sheets in place. The surface of the calendar pad is then substantially flush with the surface of the backing sheet 27.

The plastic trim indicated in general by the numeral 32 is provided with opposed parallel edge portions 33, a connecting top portion 34, and a connecting bottom strip 35. The plastic trim is secured to the backing sheet 27 in the same manner that the plastic trim 22 is secured to the backing sheet 10 in the calendar A. Lugs 36 on the rear surface of the plastic trim extend through suitable apertures or recesses 37 in the offset edge flanges 39 formed on either side of the body 27 of the background sheet. As has been previously described and illustrated in Figures 4 and 5 of the drawings, the lugs 36 are riveted over as passing through the apertures 37 to hold the plastic trim securely to the background sheet 27. The plastic trim 32 extends forwardly from the face of the background sheet 27 in order that light transmitted therethrough may cast some rays upon the background sheet. Thus the background sheet is illuminated to some extent and as the plastic trim is colored a colored glow is cast over the entire sheet. The bottom strip 35 is formed similarly to the bottom strip 24 of the calendar A and is provided with a lip 40 which overlies the forward surface of the lower edge of the sheets 30 to hold these sheets flat. The ears 31 extend through the sheets 30 near the upper edge thereof and the lip 40 extends over the lower edge of the sheets, thus holding the sheets in flat condition. The bottom edge of the backing sheet 27 adjacent the recessed portion 29 is bent rearwardly at 41 to provide sufficient space interiorly of the lip 40 to hold the sheets 31 in proper position.

In Figures 8, 9 and 10 of the drawings, I disclose a modified form of construction illustrated in general by the letter C. In this form of construction, the backing sheet 42 is provided with a recessed portion 43 into which may fit the calendar pad sheets 44 secured in place by ears 45 which extend through the sheets and are bent over the outermost sheet to hold the various sheets in place. A decorative side element 46 is positioned on each side of the sheets 40 and a rearwardly bent flange 47 encircles the edge of the calendar backing sheet 42 to strengthen and reinforce the same. A supporting stand 49 is cut from the body of the backing sheet 42 within the recessed portion 43, the forward surface of which is covered by the calendar pad sheets 44, these sheets thus concealing the opening formed therein. Figure 10 shows the standard or brace 49 in unfolded position, while Figure 9 illustrates

the standard in supporting position bent rearwardly from the backing sheet 42.

On opposite sides of the calendar pad sheets 44 and interposed between these sheets and the decorative side elements 46, I provide a slot 50 having the marginal edges bounding the same bent rearwardly as best illustrated in Figure 14 of the drawings. These rearwardly bent edges or flanges 51 engage the opposed sides of a strip 52 of transparent or translucent plastic which projects forwardly from the body portion 42 and transmits light passing through the plastic over the surface of the background sheet 42. Thus this type of calendar has most of the advantages of the previously described types of construction, as light passing through the plastic is transmitted to the forward surface of the calendar and if this plastic is of colored material, casts a colored glow over the calendar surface.

In Figures 11, 12 and 13 of the drawings, I disclose a somewhat similar type of construction to that illustrated in Figures 8, 9 and 10. This type of calendar illustrated in general by the letter D, comprises a background sheet 53 having a central recessed portion 54 designed to accommodate a series of calendar pad sheets 55. Ears 56 bent from the body of the offset portion 54 extend through the sheets 55 and are bent to overlie the forward surface of the outermost sheet 55 to hold the sheets in place. On either side of the offset portion 54 I provide a decorative side portion 57 of any configuration. An edge flange 59 extends about the entire body 53 to reinforce the body and to strengthen the same.

Positioned above and below the calendar pad sheets 55 in substantially parallel relation, I provide slots 60 and 61, respectively, having marginal edge flanges 62 to line the side edges of the slots. Within the slots 60 and 61 and frictionally engaging the flanges 62, I provide strips 63 of transparent or translucent plastic or the like, through which light may be transmitted.

On either side of the calendar pad sheets 55 and between the calendar pad sheets and the decorative side elements 57, I provide a pair of slots which are lined with side edge flanges 62. Engaged in the slots 64, I provide strips 65 of plastic or other translucent and transparent material through which light may pass. It will be understood that the plastic strips 63 and 65 extend forwardly from the body of the calendar and thus transmit light to the forward face or surface of the calendar. If the plastic strips are formed of transparent material of a colored type, the light passing through the calendar from the rear thereof will cast a colored glow over the entire surface of the calendar. A supporting stand 66 is cut from the body of the offset portion 54 of the calendar and is shown in Figure 12 bent into position to support the calendar, whereas in Figure 13, the stand is shown in inoperative position.

In Figure 15 of the drawings, I disclose a plastic strip 67 which is six-sided and which may be used in place of the outwardly rounded plastic strips previously described. The strip 67 is shown frictionally engaged in a slot 69 but it will be understood that this type of plastic strip may be used in any of the slots such as 50, 60, or 64 which have been previously described.

A circular strip 70 of plastic is shown in a groove 71 which may take the place of any of the previously described grooves. In Figure 17 of the drawings a strip of plastic 72 is shown frictionally engaged in a slot 73. Obviously these

forms of plastic strips could be substituted for the shape of plastic strip shown engaged in the slots 50, 60, 61 and 64, previously described.

It will be noted that in the constructions shown in Figures 8 through 13 of the drawings, the plastic does not extend over the lower edges of the calendar pad sheets. From an examination of Figures 9 and 12 of the drawings, it will be noted that the lower edge 74 of the offset portion 43 of the calendar C and the lower edge 75 of the offset portion 54 of the calendar D, are bent rearwardly to provide a free lower edge and to permit the sheets 44 or 55 to be bent rearwardly to some extent at their lower extremity. The edge 11 of the calendar C adjacent the offset or recessed portion 43 along the lower edge thereof, overlies the lower extremity of the sheets 44 to hold these sheets in flat condition. Similarly, the edge 19 of the calendar D adjacent the lower extremity of the calendar pad sheets 55, overlies the outer surface of these sheets to hold the same in flat condition. Thus in both of the constructions C and D, the sheets are held flat so that they will be readily readable at all times.

In accordance with the patent statutes I have described the principles of construction and oper-

ation of my calendar and while I have endeavored to set forth the best embodiments thereof, I desire to have it understood that these are only illustrative of a means of carrying out my invention and that obvious changes may be made within the scope of the following claims without departing from the spirit of my invention.

I claim:

1. A calendar comprising a background sheet, a calendar pad secured to said background sheet, a plastic framing member engaging the edges of said background sheet, said background sheet having spaced recesses therethrough, and lugs on said plastic member extending through said recesses to hold said plastic framing member to said background sheet.

2. A calendar comprising a background sheet, a pair of opposed edge flanges on said background sheet having recesses therethrough, a calendar pad secured to said background sheet, a plastic framing trim member overlying said flanges, and lugs on said plastic framing trim member extending through said recesses in said flanges securing said plastic trim member to said background sheet.

MARTIN E. TROLLEN.
